Inventor

Joseph E. Downer.

UNITED STATES PATENT OFFICE.

JOSEPH E. DOWNER, OF ALLENPORT, PENNSYLVANIA.

ANTIFRICTION-BEARING.

No. 922,864.

Specification of Letters Patent. Patented May 25, 1909.

Application filed May 29, 1908. Serial No. 435,756.

To all whom it may concern:

Be it known that I, JOSEPH E. DOWNER, citizen of the United States of America, residing at Allenport, in the county of Washington and State of Pennsylvania, have invented certain new and useful Improvements in Antifriction-Bearings, of which the following is a specification, reference being had therein to the accompanying drawing.

10 This invention relates to certain new and useful improvements in bearings, and the invention relates more particularly to a bearing adapted to be used in the journal boxes of pit cars.

15 The invention has for its primary object to provide a novel form of bearing not necessitating the use of a lubricant, wherein novel means is employed for removing all dirt and dust from the journal box in connection with 20 which it is used.

Another object of this invention is to provide a novel form of bearing for the spindles of axles or for shafts which will be extremely simple in construction, strong and durable, 25 comparatively inexpensive to manufacture and highly efficient for the purposes for which it is used.

With the above and other objects in view, which will more readily appear as the nature 30 of the invention is better understood, the same consists in the novel construction, combination and arrangement of parts to be hereinafter more fully described and claimed, and referring to the drawing accompanying 35 this application, like characters of reference designate corresponding parts throughout the several views in which:—

Figure 1 is a vertical sectional view of a journal box equipped with my improved bearing, Fig. 2 is a longitudinal sectional view of the same, Fig. 3 is a side elevation of a roller illustrating a slightly modified form of construction.

In order that the application of my improved rollers to a shaft or spindle of an axle 45 may be fully understood, I have illustrated in the accompanying drawing, a conventional form of journal box as commonly carried by an ordinary type of pit car, the journal box forming an annular opening 2 into which the spindle 3 of an axle 4 extends; the axle being provided with an annular collar 5 which heretofore limited the movement of the spindle within the journal box and 55 served functionally as a dust guard.

My invention resides in the use of a plurality of rollers within the journal box A, half of said rollers being of greater diameter than the other of said rollers, the latter serving functionally as spacers for the main rollers. The main rollers 1, which in the present instance are four in number, are formed with a cylindrical body portion 5' having cone-shaped ends 6, 6. The rollers are preferably constructed of the best of steel, which may be hardened to withstand the wear and tear to which they are subjected. The spacing rollers 7, as they will be hereinafter termed, are also four in number and are of a less diameter than the main rollers 1, 1. The spacing rollers 7 are formed of a cylindrical body portion having an annular contracted center portion 8 and cone-shaped ends 9, 9 similar to the main rollers 1, 1. All of the rollers, eight in number, are adapted to bear 75 upon the spindle 3 of the axle 4, while the main rollers 1, 1 only bear against the inner walls of the journal box A. The cone-shaped ends of the rollers are adapted to engage the collar 5 of the axle 4 and a plate 9' secured to 80 the journal box A. The collar 5 and the plate 9' are adapted to take up the end thrusts of my improved rollers.

A modified form of spacing rollers is illustrated in Fig. 3 wherein the contracted center portion 11 of the roller 12 is of a greater length than the central portion of the roller 7, while the ends of the rollers 12 are more abruptly tapered, than the cone-shaped ends of the spacing roller 7.

By the novel construction of my improved rollers it is not essential that a lubricant be used in connection with the same, although if a lubricant is used, a very small quantity will suffice in maintaining a perfect bearing 95 of the spindle 3 within the journal box A.

I do not care to confine myself to the number of main rollers or spacing rollers used in a journal box or to their size, proportion and minor details of construction, and such changes as are permissible by the appended claim, may be resorted to without departing from the spirit and scope of the invention.

What I claim and desire to secure by Letters Patent, is:—

In a roller bearing, the combination with a spindle, a journal box receiving the spindle, a bearing-collar mounted on the spindle, and an end plate for the journal box, said end plate receiving a spindle and also constitut- 110

ing a bearing plate, of a plurality of main rollers spaced apart and peripherally engaging the spindle and the journal box, said main rollers having conical ends seated against said bearing collar on the spindle and bearing plate of the journal box, and spacing rollers frictionally engaging the main rollers having conical ends engaging the bearing collar on the shaft and the end plate of the

journal box and having reduced central por- 10 tions.

In testimony whereof I affix my signature in the presence of two witnesses.

JOSEPH E. DOWNER.
